signors, by mesne assignments, to Research
Corporation, New York, N. Y., a corporation of
New York

Application May 10, 1946, Serial No. 668,948

12 Claims. (CL. 21—74)

1

This invention relates to the sterilization of air, and more particularly to the sterilization of air in places such as dormitories, hospitals, and auditoriums, where people are exposed to cross infection by air-borne bacteria and viruses.

We use the term "air sterilization" as meaning the killing of air-borne bacteria, viruses, and molds, which invade the body through the respiratory tract. The problem of air sterilization is particularly acute in indoor public gathering places, hospitals, and living places for housing large numbers of people where, through opportunity for cross infection from one person to another, the chances of infection of an individual are increased.

It has been found that introducing vapors of high boiling point polyhydroxy compounds into the air of an occupied space effects air sterilization. Vapors of triethylene glycol, propylene glycol, or ethylene glycol, are particularly effective. A concentration of triethylene glycol ranging from 0.003 to 0.005 milligram per liter of air (0.0013 to 0.0022 grain per cubic foot) produces substantially instantaneous killing of bacteria sprayed into the air containing the triethylene glycol. Similar results are obtained with concentrations of 0.1 to 0.2 milligram per liter of air (0.044 to 0.088 grain per cubic foot) with propylene glycol. Optimum results are obtained if the humidity is 35% to 45%.

An obvious method of introducing and distributing glycol vapors in an enclosed space is to introduce the vapors into existing air conditioning, ventilating, or heating ducts. However, this method has several objections. The variable conditions of temperature and humidity present in air conditioning, ventilating, or heating ducts necessitated by changing weather affect the concentration of glycol vapors present in the duct. These variable conditions alter the amount of glycol vapor which can be held in air, thereby making it extremely difficult to maintain a substantially uniform glycol vapor concentration. If metal ducts are used, the problem of condensation of glycol on the metal presents itself. Glycol has a high affinity for metal, and will condense thereon easily, particularly with a drop in temperature. Since high concentrations of glycol are required in a distribution duct for introducing glycol vapor into an air space, condensation of

2

glycol on metal surfaces in the duct results not only in inefficient operation, but also in dripping of the condensate upon the floor and furnishings of the space to be treated.

5 We avoid these objections by recirculating the air in the enclosed space, such as a dormitory room, at room temperature through a distribution system which inhibits vapor condensation therein, and introducing bactericidal vapors into the distribution system as the air circulates therethrough. The bactericidal vapors (glycol vapors being assumed as an example) enter the distribution system at a temperature elevated above that of the air in the enclosed space, such as a dormitory room, so that there is no tendency for the glycol to condense as it enters the distribution system.

20 In practicing our invention, we utilize a non-metallic means for conveying a mixture of vapor and air, such as a mixture of glycol vapor and air, of relatively high glycol vapor concentration to a plurality of outlets for securing uniform distribution of the mixture into the treated space. The problem of temperature change, which would tend to condense the glycol vapor, is overcome by recirculating the air at room temperature or by pre-heating it prior to introducing it into the distribution system. A further factor in preventing glycol vapor condensation is the introduction of

25 the glycol vapor into the distribution system at a point remote from metallic surfaces. In order to sterilize effectively the air in an enclosed space by using glycol vapors as the sterilizing medium and where glycol vapors are introduced into the air through a distribution system, it is desirable to have a concentration of glycol vapors in the distribution system from 10 to 200 times the concentration desired in the treated space. To achieve this desired concentration, it is necessary to provide a distribution system which, when glycol vapors are introduced into it, will have a minimum condensing effect upon these vapors. Furthermore, it is necessary to control the temperature of the air passing through the distribution system and the temperature of the glycol-vapor-air-mixture which is introduced into the distribution system in such a manner that condensation will be inhibited.

45 50 Accordingly, it is an object of this invention to provide a new and improved method and ap-

paratus for effecting sterilization of air by circulating the air through a distribution system and introducing bactericidal vapors into said system as the air passes therethrough.

Other objects of this invention are to provide a new and improved method and apparatus for maintaining a substantially constant predetermined concentration of bactericidal vapors in the air to be sterilized; to provide a method and apparatus for sterilizing air in which the apparatus used is independent of existing air conditioning systems, and in which the rate of flow of air through the apparatus, the air temperature, and humidity are controllable to maintain the bactericidal vapors introduced into said apparatus in vapor form; to provide a new and improved method and apparatus for sterilizing the air in an enclosed space by recirculating the air through a duct distribution system and introducing bactericidal vapors of substantially higher concentrations than the concentration desired in the treated space into the air passing through the duct distribution system.

These and other objects and advantages of our invention will become apparent from the following detailed description taken in conjunction with the attached drawings, in which

Fig. 1 is a front elevational view showing a distribution duct with a blower and vaporizer attached thereto, the vaporizer being shown 30 partly in cross section;

Fig. 2 is a diagrammatic showing of a room containing a distribution duct having a blower and vaporizer attached thereto;

Fig. 3 is a front elevational view, in cross section, of one form of vaporizer that can be used;

Fig. 4 is a front elevational view, in cross section, of another form of vaporizer that can be used; and

Fig. 5 is a front elevational view, in cross section, of still another form of vaporizer that can be used.

In Fig. 1, we have illustrated one embodiment of our invention in which a main distribution duct 10 has attached thereto a blower assembly 11 for forcing air through the duct 10 and a vaporizer assembly 12 for introducing bactericidal vapors into the distribution duct 10.

As is shown in Fig. 2, the distribution duct 10 normally extends the length of the space to be treated, such as a room 13, and contains a plurality of spaced outlets 14 for distributing bactericidal vapors into the air space of room 13. The air in room 13, or, if desired, outside air pre-heated to room temperature can be used, is drawn into the inlet opening, not shown, of blower 11, and is forced through the blower into the blower discharge outlet 15. The discharge outlet 15 will normally be made of metal, as will the rest of the blower assembly 11. To minimize the amount of metal duct used in our apparatus, the discharge outlet 15 extends only to point 16, where the main distribution duct 10, which is non-metallic, is attached. Duct 10 may be made of any suitable material which will resist the possible corrosive action of bactericidal vapors and which will inhibit condensation of these vapors. When glycol vapors are used as the sterilizing medium, and particularly if triethylene glycol vapors are used, we have found it desirable to use a treated asbestos duct, treated to be glycol resistant. As previously indicated, the main distribution duct 10 is connected to the discharge side of the blower 11 at 16.

The vaporizer assembly 12 is connected to the

distribution duct 10 adjacent the discharge side of the blower 11, as is shown in Fig. 1. This insures that the high concentration values of bactericidal vapors that are introduced into duct 10 are introduced as far as possible away from the metallic surfaces in the blower 11.

The form of vaporizer illustrated in Figs. 1 and 3 includes a branch duct 17 joined to the main distribution duct 10 at 18, a second branch duct 19 joined to the main distribution duct 10 at 20, and a connecting duct 21 connecting the two branch ducts 17 and 19. The branch ducts and connecting duct are conveniently housed in a housing 46, which also houses a source of bactericidal liquid 22 supported from the housing 46 by support member 23. In practice, the housing 46 can be made in compact closet form with a door which can be opened to permit ready inspection of the vaporizer assembly and to permit removal and replacement of the bactericidal liquid source 22. The branch ducts 17 and 19 and connecting duct 21 are located vertically below the main distribution duct 10. Likewise, the major portion of the housing 46 extends vertically below the main distribution duct 10, and the housing 46 is supported at the top, as indicated at 43 in Fig. 1, by the main distribution duct 10. It will be observed that the branch ducts 17 and 19 and connecting duct 21 are in U-shape form.

Referring more particularly to Fig. 3, it will be noted that the branch duct 19 contains a plurality of baffles 24 which extend transversely of duct 19, and which are staggered with respect to each other. Baffles 24 may be either of half-moon shape, of segmental type, or perforated. The number of baffles used will depend upon the maximum rate of evaporation desired. The individual baffles extend more than half way across the diameter of duct 19 so as to cause a fluid medium, such as an air current, to traverse a tortuous path in moving through the duct. The baffles are arranged either horizontally or, preferably, sloping downward slightly, so as to allow a liquid medium, such as a bactericidal liquid, to pass by the action of gravity from one to the other, and also to prevent splashing or the admission of large drops or droplets of liquid into the main distribution duct 10. They are fitted in such a manner that they may be removed easily for cleaning. The baffles may be made of metal, which is treated to be corrosion resistant.

Bactericidal liquid, triethylene glycol being assumed as an example, is fed at a controlled rate into the upper part of duct 19 from a source 25. This feeding can be accomplished by gravity, pump, or any convenient means. As is shown in Fig. 3, it is preferable to feed under the first baffle 26 and onto the upper surface of the second baffle 27. Feeding under the first baffle 26 minimizes the opportunity for droplets of liquid to enter main distribution duct 10. The liquid passes from the top of one baffle to the top of the next succeeding baffle immediately below by the action of gravity until substantially all of the baffles have liquid on their upper surfaces and liquid passing or dripping between these surfaces.

A portion of the air passing through the main distribution duct 10 is diverted into duct 17 at point 18. This air passes through duct 17 and into duct 21, where, in turn, it passes over a plurality of heating elements 28, which raise the temperature of the air. The air then passes into duct 19, being aided by deflector plate 29, and winds past the baffles 24 before reentering

the main distribution duct 10 at 20. The heated air in passing over the baffle surfaces which contain bactericidal liquid, triethylene glycol being assumed as an example, vaporizes the triethylene glycol, and the mixture of air and triethylene glycol vapors passes into duct 10. To facilitate the reentry of the air into duct 10, a venturi 30 is provided, which creates a low pressure region adjacent the exit from duct 19. The low pressure point existing in the main distribution duct 10 adjacent the exit from duct 19 at 20 not only facilitates the reentry of air into duct 10 at that point, but also creates a pressure differential, which causes air to be diverted from the main distribution duct 10 through ducts 17, 21, and 19 back into the main distribution duct 10. Bactericidal liquid which is not vaporized is collected in a well 31, and can be drained from the well through an outlet 32 having a manually operated valve 33. When the level of the liquid in the well 31 becomes too high, such as could occur if the blower 11 stopped and hence air flow through the vaporizer assembly 12 ceased, with the result that bactericidal liquid would not be vaporized but would merely collect in the well 31, a liquid level control 34 is provided which actuates a solenoid valve 35 to cut off the supply of liquid to the baffle members 24. In order to vary the amount of air which passes through vaporizer assembly 12, a rotatable damper 36 is provided.

Instead of diverting air from the main distribution duct 10 through the vaporizer assembly 12, a separate air feed could be provided for the vaporizer. This is illustrated in Fig. 4 in which a separate fan means 37 forces air through a duct 38, over a heating element 39, and past a plurality of baffle members 40. Otherwise, the operation of this vaporizer is the same as that illustrated in Fig. 3.

Another means to effect circulation of air past the baffle members and into main distribution duct 10 is illustrated in Fig. 5. In the construction illustrated in this figure, a "chimney draft" effect is obtained by positioning a heating coil 41 at the bottom of a columnar housing 42, which contains a plurality of staggered baffles 44 arranged in the manner previously described. Air enters the bottom of the columnar housing 42 at inlet 45, and comes into contact with heating coil 41. As the air is heated, it rises, thereby winding past the baffles 44, vaporizing the bactericidal liquid, and passes into the main distribution duct. The mixture of vapors and air passes into the main distribution duct 10 in the manner previously described for the apparatus illustrated in Figs. 3 and 4. In all of these various modifications, it is preferable to introduce the mixture of bactericidal vapors and air into the main distribution duct at a low pressure point therein, such as is created by venturi 30.

When the bactericidal vapors enter the main distribution duct, they are forced through the duct and out of the outlets 14 by action of the blower assembly 11. The distance between the outlets 14 is dependent upon the characteristics of the space to be treated. Preferably, the size of the outlets 14 is such that they have the characteristics of an orifice; that is, the output from them should be proportional to the square foot of the static pressure in the duct 10. Utilizing outlets having this characteristic will insure uniform delivery of vapors and air from the outlets throughout the length of duct 10. Furthermore, this uniformity increases with the static pressure maintained by the blower 11. If desired, branch

take-offs may be installed to pipe the bactericidal vapors about the space to be treated.

As an example of the practice of our invention, a satisfactory concentration of triethylene glycol vapors can be maintained in a dormitory of assumed proportions—say, 120 feet long by 30 feet wide by 9 feet high, utilizing the following procedure and apparatus: A 6-inch glycol-resistant asbestos distribution duct extends substantially the length of the dormitory adjacent the ceiling thereof. This duct contains openings spaced anywhere from 3 feet to 12 feet apart. Each opening is approximately 2 inches in diameter and has the characteristics of an orifice. The distribution duct is connected to a recirculating blower assembly, which is controllable to move air through the distribution duct at a rate of from 300 to 800 cubic feet per minute at a static pressure of 8 inches Hg. A concentration of glycol vapors from 10 to 200 times the concentration desired in the treated space can be secured in the distribution duct by varying the amount of air which passes through the vaporizer assembly. The vaporizer assembly is attached to the main distribution duct, and consists of asbestos ducts, as is illustrated in Fig. 1. When the air passing through the vaporizer contacts the baffles, it is at a temperature of from 200 to 250 degrees F. The air which reenters the distribution duct as it is recirculated, and consequently which is introduced into the vaporizer, is at room temperature—say, from 55 to 80 degrees F. The complete cycle of operation, then, is that air enters the blower; passes through the blower; is discharged into the main distribution duct; a portion of the air is diverted into the vaporizer, is preheated, vaporizes the bactericidal liquid; the bactericidal vapors and air then reenter the main distribution duct, where they are forced along the duct and out of the outlets; vapors then disperse throughout the space to be treated; and the air in this space is then redrawn into the blower.

It will thus be seen that we have provided a method and apparatus for achieving sterilization of air in which the air is circulated and, while it is being circulated, bactericidal vapors are introduced into it in a concentration sufficiently high to maintain the concentration desired in the space being treated. Furthermore, maintenance of the desired concentration is furthered by minimizing possibilities of vapor condensation. The apparatus which is used to accomplish this result is not complicated, is easy to install and maintain, and is efficient in operation.

While we have described particular embodiments of our invention and the method of practicing said invention, we do not wish to be restricted thereto, but intend to cover all modifications thereof which would be apparent to one skilled in the art and which come within the true spirit and scope of our invention.

We claim:

1. An air sterilization apparatus comprising a distribution duct having a plurality of spaced outlets therein for distributing a mixture of air and bactericidal liquid vapors to the air in a space to be treated, a blower arrangement for forcing said mixture through said duct and out of said outlets, a U-shaped branch duct arrangement connected to the distribution duct adjacent the discharge side of said blower, each end of said U-shaped branch duct arrangement opening into the distribution duct, a construction in said distribution duct adjacent the end of said U-shaped

branch duct arrangement farthest from the discharge side of said blower whereby the pressure in the distribution duct is reduced at this point thereby causing a portion of the air passing through the distribution duct to pass through the U-shaped branch duct arrangement and re-enter the distribution duct adjacent the constriction therein, and means to cause the air passing through the U-shaped branch duct arrangement to vaporize bactericidal liquid therein whereby said air will contain bactericidal liquid vapors as it reenters the distribution duct.

2. An air sterilization apparatus comprising a distribution duct having a plurality of spaced outlets therein for distributing a mixture of air and bactericidal liquid vapors to the air in a space to be treated, means causing said mixture to flow through said duct and out of said outlets, a U-shaped branch duct arrangement connected to the distribution duct adjacent the discharge side of said flow causing means said U-shaped branch duct arrangement extending vertically below said distribution duct and each end of said U-shaped branch duct arrangement opening into said distribution duct, a Venturi arrangement located in said distribution duct adjacent the opening therein forming the end of the branch of the U-shaped duct arrangement farthest from the discharge side of said flow causing means whereby the static pressure in said distribution duct is reduced at this point thereby causing a portion of the air passing through the distribution duct to pass through the U-shaped branch duct arrangement and reenter the distribution duct adjacent the Venturi arrangement, means for controlling the amount of air passing through said U-shaped branch duct arrangement, and means for causing said air to vaporize bactericidal liquid contained within said U-shaped branch duct arrangement whereby said air contains bactericidal vapors as it reenters the distribution duct.

3. An apparatus for introducing bactericidal liquid vapors into the air of an enclosed space comprising a substantially horizontal distribution duct for distributing a mixture of said vapors and air to the air in the enclosed space, a blower arrangement for forcing said mixture through said duct, a U-shaped branch duct arrangement connected to and extending vertically downward from said distribution duct adjacent the discharge side of said blower, each end of said U-shaped branch duct arrangement opening into the distribution duct, means for diverting a portion of the air passing through the distribution duct through said U-shaped branch duct arrangement, means for heating said diverted air and means for bringing said heated diverted air into contact with a plurality of bactericidal liquid containing surfaces to cause liquid on said surfaces to be vaporized whereby the air reentering the distribution duct contains bactericidal liquid vapors.

4. An apparatus for introducing triethylene glycol vapors into the air in an enclosed space comprising a distribution duct for distributing a mixture of air and triethylene glycol vapors into the air in said enclosed space, a blower arrangement for forcing said mixture through said duct and into the air in said space, means for diverting a portion of the air passing through said distribution duct through a U-shaped branch duct arrangement and back into said distribution duct, means for heating said diverted air to a temperature sufficient to cause vaporization of the triethylene glycol liquid, and means for bringing said

heated air into contact with the triethylene glycol liquid whereby the air reentering the distribution duct contains triethylene glycol vapors.

5. An apparatus for recirculating the air within an enclosed space and for continuously introducing into said air during recirculation thereof vapors of triethylene glycol comprising an asbestos distribution duct having a blower connected thereto, a U-shaped branch asbestos duct arrangement connected to said distribution duct adjacent the discharge side of said blower, each end of said U-shaped branch asbestos duct arrangement opening into said distribution duct, means for diverting a portion of the air passing through said distribution duct through said U-shaped branch asbestos duct arrangement, means for heating said diverted air to a temperature of from 200° F. to 250° F., a plurality of transverse baffles located within a branch of said U-shaped asbestos duct arrangement, said baffles having triethylene glycol liquid on individual surfaces thereof, and means to bring said heated air into contact with said baffle surfaces whereby the triethylene glycol liquid is vaporized and the air reentering the main distribution duct contains triethylene vapors.

6. In an apparatus for effecting sterilization of the air in an enclosed space having means for recirculating the air in said space and means for introducing bactericidal liquid vapors into said air as it is recirculated, a vaporizer comprising a columnar housing, a plurality of baffles located within said housing and extending transversely of the longitudinal axis thereof, said baffles being staggered with respect to each other and each individual baffle blocking off more than half of the diameter of said columnar housing, means to feed bactericidal liquid onto the upper surfaces of said baffles, means to collect excess liquid fed to said baffles, a source of air, means to heat said air, means to force said air past said baffles, and means to discontinue said liquid feed to said baffles upon failure of air flow past said baffles.

7. In an apparatus for effecting sterilization of the air in an enclosed space having means for recirculating the air in said space and means for introducing bactericidal liquid vapors into said air as it is recirculated, a vaporizer comprising a columnar housing, a plurality of baffles located in said columnar housing and disposed transversely of the longitudinal axis thereof, said baffles being staggered with respect to each other, means to feed bactericidal liquid onto the upper surfaces of said baffles, said liquid feeding means being located adjacent the top of said columnar housing, means to cause air to flow past said baffles, means to heat said air prior to contact with said baffles, and means to control the amount of air flowing past said baffles.

8. In apparatus for introducing bactericidal vapors into the air of an enclosed space comprising a main duct having an outlet communicating with said enclosed space, a blower for moving air through said main duct, a branch duct communicating with said main duct between said blower and outlet, a columnar vaporizing chamber in the branch duct, means for passing air through said branch duct, the vaporizing chamber therein, and into the main duct, means for heating the air passing through said vaporization chamber, a plurality of baffles located in said columnar vaporizing chamber and disposed transversely of the longitudinal axis thereof, said baffles being staggered with respect to each other, and means for supplying

bactericidal liquid to the upper surfaces of said baffles in the vaporizing chamber for vaporization therein.

9. The apparatus as set forth in claim 8 together with means for controlling the rate of vaporization of said bactericidal liquid in said vaporizing chamber.

10. The apparatus as set forth in claim 8 in which the vaporizing chamber, that portion of the branch duct between the vaporizing chamber and the main duct, and all of the main duct extending from the point of entry of the branch duct to said outlet have a non-metallic inner surface.

11. The apparatus as set forth in claim 8 in which a Venturi device is built into the main duct at the point of entry of the branch duct, whereby the movement of air through the main duct induces a flow of air through said branch duct.

5

12. The apparatus as set forth in claim 8 in which the bactericidal liquid is triethylene glycol, and the air in the vaporizing chamber is heated to a temperature of from 200° to 250° F.
